UNITED STATES PATENT OFFICE.

JOSEPH A. DUPUIS, OF PORTLAND, OREGON.

HINGE.

1,024,837.

Specification of Letters Patent. Patented Apr. 30, 1912.

Application filed March 21, 1911. Serial No. 615,930.

To all whom it may concern:

Be it known that I, JOSEPH A. DUPUIS, citizen of the United States, residing at Portland, in the county of Multnomah and 5 State of Oregon, have invented certain new and useful Improvements in Hinges, of which the following is a specification.

This invention comprehends certain new and useful improvements in builder's hardware and relates particularly to window sashes of that type that are arranged to swing inwardly either to the right or to the left, as desired, whereby the sashes may be easily cleaned, without exposing the window 10 washer to the danger incidental to sitting or standing on the window sill so as to reach the outer surfaces of the window pane, as is rendered necessary by those sashes which merely slide, my invention being therefore 15 particularly adapted for use in the upper stories of offices or other buildings.

The invention has for its object in a window of the character above set forth, an improved construction of hinge, forming a 20 swinging connection between either side of the main portion of the sash and the pane holding frame incorporated therein, the hinges of either side being capable of disconnection, whereby the pane holding frame 25 may be swung inwardly either to the right or to the left, for the purposes of ventilation, or merely for the purpose of enabling the outer sides of the panes to be reached so as to be washed, without reaching out of 30 the window frame.

With this and other objects in view as will 35 more fully appear as the description proceeds, the invention consists in certain constructions, arrangements and combinations 40 of the parts that I shall hereinafter fully describe and claim.

For a full understanding of the invention, reference is to be had to the following description and accompanying drawings, in 45 which:

Figure 1 is a face view of a window constructed in accordance with my invention; Fig. 2 is a detail face view of one pair of hinged plates; Fig. 3 is a horizontal sectional view on the line 3—3 of Fig. 2; Fig. 4 is a 50 detail perspective view of one of the hinged bolts or pintles; Fig. 5 is a fragmentary view of the hinge plates.

Corresponding and like parts are referred 55 to in the following description and indicated

in all the views of the drawing by the same reference characters.

Referring to the drawing, 1 designates the upper sash of a window, and 2 the lower sash thereof, each of said sashes including 60 a pane carrying frame 8 to the sides of which hinged plates 9 are secured by screws or similar fastening devices, the same being arranged at opposite sides of the frames 8 in pairs, as shown.

Each hinge plate 9 is formed with an upper pair of apertured ears 10 spaced from each other, and a corresponding pair of lower ears spaced from the upper pair, the ears being preferably formed by curling 70 the metal of which the plates 9 are composed. Upper and lower bolts 12 are mounted for longitudinal movement in the ears 10 and 11, respectively, said bolts being encircled by springs 13, whereby they are held in operative position and being provided at their adjoining ends by finger pieces 14, whereby they may be easily retracted by merely pressing said finger piece together. The bolts 12 are formed with beveled outer ends 75 15 designed to engage beveled ears 16 formed at the top and bottom of complementary hinge plates 17 secured by screws or the like to the walls of the main portions 80 of the sashes. By the beveled construction 85 of the ends 15 and ears 16, it is obvious that the hinges may be automatically connected together, merely by swinging the open frame to a closed position. It is also evident that, as these hinges are alike on both 90 sides of the sashes, the pane holding frames may be swung inwardly either to the right or to the left. It is, of course, to be understood that the frames 8 may have screen 95 frames substituted for them, as it is possible to entirely remove the frames 8, whenever desired.

18 designates a lock positioned at the meeting rails of the sashes. This may be of any desired construction, as is manifest.

From the foregoing description in connection with the accompanying drawing, the operation of my improved window sash will be apparent.

It is possible for either of the pane carrying frames to be swung inwardly, when desired, either to the right or to the left, so as to open the window in this manner for the purpose of cleaning the panes or for any other purpose.

It is to be understood that my improved construction of hinge can be used on doors; for instance on outside doors to change same from panel or glass to screen and vice versa, if desired.

Having thus described the invention, what is claimed as new is:

A hinge of the character described, comprising complementary plates one of which 10 is formed with two pairs of apertured ears, the ears of each pair being spaced from each other and one pair of ears being spaced from the other, bolts mounted for longitudinal movement in the respective pairs of ears, 15 springs mounted between the ears of each pair and encircling the bolts and tending to move said bolts outwardly whereby the

outer ends of the bolts will protrude outwardly from the outermost ears, the bolts being provided at their adjoining ends with 20 finger-pieces and the other plate being formed at its ends with apertured ears spaced apart a distance to overlap the outer sides of and contact with the outermost ears of the first-named plate and designed 25 to be engaged by the protruding ends of the bolts.

In testimony whereof, I affix my signature in presence of two witnesses.

JOSEPH A. DUPUIS. [L. S.]
